2 Claims. (Cl. 53—169)

The present invention relates to means for closing filled match-boxes having the innerbox partially inserted into the outerbox by means of a closing device operating on the ends of the inner- and outerboxes, respectively.

Closing of filled match-boxes has previously taken place directly after filling of the boxes. It has therewith proved impossible to avoid damage arising both to the boxes and the matches owing to the fact that the matches often project beyond the edges of the innerbox and are jammed when the box is closed. By transferring the filled boxes to the closing means with the inner box partially inserted into the outerbox via a conveyor it has been possible to arrange a correction of the positions of the projecting matches so that the matches which do not lie correctly in the box on being fed to the closing means will only project beyond the short side of the innerbox. In this way, damage to boxes and matches during closing has only partially been avoided and until now the disadvantage has remained that the matches which at the beginning of the closing process project beyond the short side of the innerbox, despite experiments with different types of closing means, are jammed between the inner box and the outer box with the ignition heads partially projecting beyond the innerbox.

An improved arrangement for closing filled match-boxes has been effected by the present invention, the above-mentioned disadvantages being eliminated in that prior to the closing process a drive plate movable relative to the innerbox in the longitudinal direction of the box and towards the outer end of the innerbox for inserting matches projecting beyond the end of the innerbox, is arranged to be moved by its lower edge closely above the top edge of the outer end of the innerbox to a position immediately within this edge, the drive plate being arranged to retain this position relative to the innerbox during at least the principle part of the closing process. The drive plate can be attached to the closing device operating on the innerbox, which device is either securely fixed, the closing device operating on the end of the outerbox being movable, or arranged movably. In addition, the drive plate can be pivotally attached to a horizontal shaft mounted pivotally above the boxes, the shaft being at right angles to the longitudinal direction of the boxes. As the drive plate will lean at varying angles, owing to the pivotal movement, the matches projecting at different lengths from the innerbox, and consequently leaning at different angles, will be actuated principally in the axial direction by the drive plate.

The invention will be further explained in the following in connection with the attached drawing which shows an embodiment of the invention chosen as an example.

The drawing shows a longitudinal section through a closing station along a feed path for filled match-boxes. The boxes consist of an innerbox 1, which is partially inserted into an outerbox 2 and the boxes slide on a path 3 with the end of the innerbox abutting a movable carrier member 4. Above the feed path and at right angles to the direction of feed are two horizontal shafts 5 and 6, both rotatably mounted. A stop arm 7 capable of being inserted into the path of the boxes is attached to shaft 5 and a drive plate 8 is attached to the shaft 6. The drawing shows a position immediately before the front end

2

of the outerbox 2 comes into contact with the lower stop arm 7. In this position, the drive plate 8 is caused by a cam mechanism not shown to swing forward from the position shown by solid lines to the position 8a. The pivotal movement is so adapted that position 8a relative to the box 1 is adopted in connection with starting the closing process, and the drive plate 8 is caused after this, in the position 8a relative to the innerbox, to follow the innerbox 1 during its insertion into the outerbox. During the pivotal movement to position 8a, the drive plate comes into contact with matches 9 projecting at different lengths, of which those projecting farthest normally form a greater angle with the horizontal plane than those projection least, from which it follows that the drive plate 8 can be arranged so that the matches, during the whole of the pivotal movement, are actuated by the drive plate principally in the axial direction and suitably with a light downward pressure. On passing above the upper edge of the rear edge 10 of the innerbox, the drive plate 8 forms substantially an angle of 90° with the diagonal plane of the innerbox containing this edge. Owing to the fact that the drive plate adopts the unchanged position 8a relative to the innerbox 1 during the closing process, the risk of the uppermost matches being jammed between the rear edge 10 of the innerbox and the upper side 11 of the outerbox when insertion into the outerbox 2 is completed, is substantially reduced even if the drive plate during this last phase of the closing process is permitted to maintain the position 8a relative to the innerbox 1 and thus moves past the rear edge of the upper side 11 of the outerbox, as shown in the drawing.

A similar operation is obtained on using the drive plate 13 resiliently attached to the stop arm 7, the drive plate having the task of making possible the closing of match-boxes fed with the outerbox abutting the carrier member 4. The innerbox 1 will be pushed in under the drive plate 13 which here has the position marked 12, until the box strikes against the stop arm 7. The matches which project farthest out of the innerbox will normally at first come into contact with the upper portion of the drive plate, and those which project least will come into contact with portion 13a of the drive plate, which portion forms an angle of substantially 90° with a plane through the upper edge of the outer side of the innerbox and the central point of the bottom of the innerbox.

A substantial advantage of the drive plate 8 is that it can easily be adapted with regard to different types of match-boxes and matches to obtain satisfactory closing. The drive plate 8 can thus be arranged to graze or substantially to graze both to the edge 10 of the innerbox or both its longitudinal edges and the rear upper edge of the outerbox 2. The bottom portion of the drive plate 8 can also be arranged to abut the end of the outerbox 2 and possibly also the upper edges of the innerbox 1 during the last phase of the closing process in order, as effectively as possible, to eliminate the risk of matches being jammed between the edge 10 of the innerbox and the upper side 11 of the outerbox.

What is claimed is:

1. A device in match making machines for closing filled match-boxes, each match-box consisting of a filled innerbox partially inserted into an outerbox and being conveyed by a conveyor having moving carrier members pushing on the outer ends of the innerboxes, said device comprising a stop arm, means to insert said stop arm into the path of movement of the match-boxes and to withdraw said stop arm after closing of each match-box, a horizontal shaft rotatably mounted above the conveyor at right angle to the direction of movement of the conveyor, a drive plate attached to said shaft and adapted to push the ends of matches protruding beyond the outer end of the innerbox, said shaft pivoting said drive

plate prior to the closing operation, towards and over the outer end of the innerbox to a position immediately within the outer end of the innerbox and maintaining said drive plate in this position relative to the innerbox during at least the principle part of the closing operation and said shaft being positioned so that said bottom edge of the pivoting drive plate is substantially at a tangent both to the top edges of the innerbox and the top edge of the end of the outerbox facing the innerbox.

2. A device as claimed in claim 1, wherein comprising a drive plate has a bottom portion that when passing above the top edge of the outer end of the innerbox forms

substantially an angle of 90° to the diagonal plane of the innerbox containing this edge.
